UNITED STATES PATENT OFFICE.

FRANK RHIND, OF MERIDEN, CONNECTICUT.

DESIGN FOR A LAMP-BURNER.

SPECIFICATION forming part of Design No. 21,770, dated August 9, 1892.

Application filed June 11, 1892. Serial No. 436,391. Term of patent 14 years.

To all whom it may concern:

Be it known that I, FRANK RHIND, a citizen of the United States, residing at Meriden, in the county of New Haven and State of Connecticut, have invented a certain new and original Design for Lamp-Burners, of which the following is a full, clear, and exact description, reference being had to the accompanying drawing, forming a part thereof, and which shows in elevation a lamp-burner conformed and ornamented in accordance with my design.

The leading feature of my design consists in the ornamental band or zone which occupies the center of the burner and contrasts upon the one side with the smooth plain top of the deflector and upon the other side with the smooth band which lies below it.

In the drawing, A denotes the cone-shaped

deflector, whose surface is smooth and plain. 20 Below this is a zone or belt B, which occupies approximately the central one-third of the burner in height and which is ornamented with figures stamped thereon in relief—as shown, for instance, at C. Below this band 25 is a bead D, unprovided with any ornament, so as to form a contrast for the ornamental band below the latter, as the top of the deflector does above it.

I claim—

The design for a lamp-burner, as herein shown and described.

In testimony whereof I affix my signature in presence of two witnesses.

FRANK RHIND.

Witnesses:

S. H. HUBBARD,

M. C. HINCHCLIFFE.
